DESK BASE FOR A WRITING INSTRUMENT

Walter Irion Bieger, Janesville, Wis., assignor to The Parker Pen Company, Janesville, Wis., a corporation of Wisconsin

Filed Mar. 26, 1959, Ser. No. 55,181

Term of patent 14 years

(Cl. D74—1)

Fig. 1 is a top plan view of a desk base for a writing instrument embodying my new design;

Fig. 2 is a front elevational view of said base;

Fig. 3 is a side elevational view thereof; and

Fig. 4 is a perspective view thereof, the dotted line partial showing of a writing instrument being for illustrative purposes only.

I claim:

The ornamental design for a desk base for a writing instrument, as shown and described.
